UNITED STATES PATENT OFFICE.

PERCIVAL SEWELL ROBARTS, OF OTTAWA, ONTARIO, CANADA.

MATCH-STRIKER.

1,212,810.

Specification of Letters Patent. Patented Jan. 16, 1917.

Application filed January 28, 1916. Serial No. 74,924.

To all whom it may concern:

Be it known that I, PERCIVAL SEWELL ROBARTS, a subject of the King of Great Britain, and resident of Ottawa, in the 5 Province of Ontario, Canada, have invented certain new and useful Improvements in Match-Strikers, of which the following is a specification.

The invention relates to improvements in 10 match strikers as described in the present specification and illustrated by the accompanying drawings that form part of the same.

My invention relates to match strikers and 15 it consists essentially in the novel construction and arrangement of parts as will be hereinafter described and particularly pointed out in the claims.

The invention relates particularly to 20 match strikers to be pinned securely to a garment, wearing apparel or the like but preferably adapted to be fastened inside a coat in any position convenient for striking matches thereon. In such a place it will lie 25 fixedly secured almost flush with the material creating no bulge or inconvenience of any kind.

Although but specific embodiments of 30 this invention are herein shown and described it will be understood that details of such construction may be altered or omitted and that the device may be made of any suitable material of any suitable size and in 35 any suitable manner without departing from the spirit of the invention as disclosed in the claims.

The objects of my invention are to provide a new simple and inexpensive match 40 striker which includes a plate with a rough surface or adapted to support a material having a rough surface and formed with the opposite ends folded to receive securing pins between said folds.

A further object is to provide a match 45 striker that in construction and use will be simple and effective.

With these and other objects in view reference is now had to the accompanying drawings in which like numerals of refer-

ence indicate corresponding parts through 50 the several figures and in which:—

Figure 1 is a perspective view. Fig. 2 is a longitudinal section. Fig. 3 is a perspective view of an alternative form. Fig. 4 is a longitudinal section thereof. 55

Referring to the drawings the match striker comprises a plate 1 consisting of any suitable material but preferably as here shown of metal, folded at the opposite ends 2 and 3 to form receptacles or holders 4 and 5 for the securing pins 6 and 7. These pins are formed of one piece of pin wire or other suitable material adapted to pass through the folded ends 2 and 3 and fixedly secured therein said pins being pointed at 60 each end and bent beneath the plate 1 to form the securing means whereby the garment is fixedly grasped and the striker fixedly held thereon.

8 and 9 are side flanges formed on the 70 plate 1 adapted, in combination with the shoulder formed by the folded ends 2 and 3, to hold an abrasive strip 10, of any suitable material.

In Figs. 3 and 4 a modification of the invention is suggested in which the plate 1 is not folded at the ends or formed with the flanges 8 and 9 and in which the abrasive material 10 is replaced by having the surface of said plate roughened. The securing 80 hooks 6 and 7 instead of being secured in the folded ends 2 and 3 horizontally are secured in any suitable manner longitudinally on the bottom of the plate and bent inwardly thereunder. 85

What I claim for my invention is:—

1. A device of the class described comprising a piece of metal cut to form a body-portion having the opposite ends folded to receive securing pins and provided with side 90 flanges to hold, in combination with said folded ends, an abrasive material.

2. The combination with a plate folded at opposite ends and provided with side flanges of an abrasive material adapted to fit therein, securing pins extending through said folded ends and inwardly bent across the back of said plate. 95

3. The combination with a plate folded at both ends and formed with side flanges of two lengths of wire formed with pointed ends fixedly secured and extending horizontally through said folded ends, the pointed ends of said wires being bent inwardly beneath said plate, an abrasive material for said plate.

In testimony whereof I have hereunto

signed my name in the presence of two sub- 10
scribing witnesses at the city of Ottawa, in
the Province of Ontario, this 15th day of
January, 1916.

PERCIVAL SEWELL ROBARTS.
